J. KRECISZ

JOINER'S PLANE

Filed Apr. 12, 1922

FIG. 1.

FIG. 2.

FIG. 4.

FIG. 5.

FIG. 6.

Inventor

John Krecisz

J. K. Bryant,
Attorney

UNITED STATES PATENT OFFICE.

JOHN KRECISZ, OF CHICAGO, ILLINOIS.

JOINER'S PLANE.

Application filed April 12, 1922. Serial No. 551,889.

To all whom it may concern:

Be it known that I, JOHN KRECISZ, a citizen of the United States of America, residing at Chicago, in the county of Cook and 5 State of Illinois, have invented certain new and useful Improvements in Joiners' Planes, of which the following is a specification.

This invention relates to certain new and useful improvements in joiners' planes and 10 has particular reference to the provision of a pair of gage bars adjustably associated with the block of the plane for varying depths of cuts of the knife.

A further object of the invention embodies in a joiner's plane of the type above set forth, the provision of a laterally adjustable side bar or gage for determining the position of a groove or channel relative to the edge of the article being grooved.

20 With the above objects in view and others that will appear as the nature of the invention is better understood, the same consists in the novel construction, combination and arrangement of parts hereinafter more fully 25 described, illustrated in the accompanying drawings, and pointed out in the appended claim.

In the drawings forming a part of this application and in which like designating 30 characters refer to corresponding parts throughout the several views:

Fig. 1 is a side elevational view partly shown in section of a joiner's plane constructed in accordance with the present invention showing the adjusting screws for shifting the gage bars relative to the cutting blade.

Fig. 2 is a top plan view of the plane showing the adjusting and clamping screws 40 associated with the laterally shiftable gage bar.

Fig. 3 is a cross sectional view taken on line III—III of Fig. 2 showing the internally threaded sleeve bearing for the adjusting screw of one of the gage bars, and

45 Figs. 4, 5, 6 and 7 show fragmentary plan views of the cutting ends of various types of blades.

The invention referring to a joiner's plane, 50 designed for forming a groove or channel in various kinds of woodwork, embodies a main body portion in the form of an elongated rectangular block 1 having a centrally

positioned slotted opening 2 provided with upper overhanging shoulders 3 for the reception of a cutting blade and wedge retaining block. The lower side of the block 1, as shown in Figs. 1 and 3, is longitudinally slotted as at 4 for the reception of gage plates positioned at opposite sides of the 60 central opening 2.

The gage plates 5 are adjustably mounted in the slots 4 for varying the depth of cuts of the blade secured within the opening 2, each block 5 receiving the lower ends of adjusting screws 6 swivelly retained therein by set screws 7, the adjusting screws 6 extending vertically through the block into internally threaded sleeves 8 countersunk within the block. The outer side wall of the 70 block 1 is suitably slotted as at 7' for permitting ready access to certain ones of the set screws 7.

As shown in Figs. 1 and 2, the cutting blade 9 having a lower cutting edge 10 is 75 positioned in the central opening 2 and rests upon the rearwardly positioned inclined wall 11 of the central opening, the blade passing beneath the shoulders 3 while a wedge block 12 interposed upon the cutting 80 blade engages the shoulders 3 wedging the blade to the block 1.

A lateral gage bar 13 is associated with the block 1, being of reversed L-shaped formation having a lower leg 14 extending beneath and towards the block 1. Screw bolts 15 having operating heads 16 freely extend through the vertical leg of the lateral gage bar 13 and are threaded into openings provided in the block 1 while position retaining screws 17 having operating heads 18 are threaded through the block 1 with the ends thereof freely engaging the lateral gage bar 13 shown in Fig. 2 to hold the gage bar rigidly positioned relative to the block 1.

As shown in Figs. 4 to 7, various types of cutting blades may be employed, Figs. 4 and 5 showing cutting planes 19 and 20 especially employed in the construction of molding strips, Fig. 6 a triangular point 21 while 100 Fig. 7 shows a curved or oval point 22.

From the above detailed description of the device it is believed that the construction and operation will now be at once apparent, it being noted that the blade 9 is anchored 105 in the block 1 by the wedge block 12 engag-

ing the shoulders 3 of the opening 2 and forcing the blade into frictional engagement with the inclined wall 11 of said opening, while the adjusting screws 6 regulate the 5 depth of cuts of the cutting ends of the different blades 9. It will be readily understood that the forward and rear gage plates, or blocks 5, are adapted to engage within the groove being cut, the depth of the finished groove being equal to the width of the protruding portion of the said blocks. The laterally adjustable gage bar 13 may be shifted to vary the distance of the cut groove from the adjacent edge of the article, the 15 laterally adjusting gage bar being maintained in its set position by the screws 17.

While there are herein shown and described the preferred embodiments of my invention, it is nevertheless to be understood that various forms, modifications and arrangements 20 of the parts may be made without departing

from the spirit and scope of the invention as claimed.

Having thus described the invention, what I claim as new is:—

In a device of the class described, a body member, a cutting blade detachably received within said body member, gage plates loosely received within grooves formed in the forward and rearward portions of the said body member at each side of the said cutting blade, and means for adjusting the position of the gage plates within their respective grooves, said means comprising vertically disposed adjusting screws swivelly retained at one end within the said gage plates and screw threadedly disposed within internally threaded sleeve members carried by the said body portion.

In testimony whereof I affix my signature.

JOHN KRECISZ.
